UNITED STATES PATENT OFFICE.

CHARLES E. HIRES, OF PHILADELPHIA, PENNSYLVANIA.

DESIGN FOR APPARATUS FOR DISPENSING AERATED LIQUIDS.

SPECIFICATION forming part of Design No. 11,699, dated March 23, 1880.

Application filed February 9, 1880. Term of patent 7 years.

To all whom it may concern:

Be it known that I, CHARLES E. HIRES, of the city and county of Philadelphia, State of Pennsylvania, have invented a Design for Apparatus for Dispensing Aerated Liquids, of which the following is a specification.

The nature of my design is fully represented in the accompanying drawing.

The figure is an elevation of the apparatus illustrating my invention.

The leading feature of my design consists in making the apparatus to represent a rustic house.

The body of the apparatus is made of wood, 15 terra-cotta, or earthenware, and is covered with roots or representations of roots. Open-

ings are formed in the front to represent a door and windows, and in front is a representation of steps. Upon the front and along the cornice of the fountain are trained vines, as shown in the figure.

Having thus described my invention, I desire to secure by Letters Patent—

The design for an apparatus for dispensing aerated liquids herein shown and described, 25 the same consisting of the representation of a rustic house having vines trained upon the front and along the cornice, as shown.

CHARLES E. HIRES.
